ATTORNEY

UNITED STATES PATENT OFFICE.

DAVID WASSERMAN, OF JERSEY CITY, NEW JERSEY.

CORNER FASTENING FOR BEDSTEADS.

Application filed October 17, 1923. Serial No. 669,038.

To all whom it may concern:

Be it known that I, DAVID WASSERMAN, a citizen of the United States, and resident of Jersey City, in the county of Hudson and 5 State of New Jersey, have invented new and useful Improvements in Corner Fastenings for Bedsteads, of which the following is a specification.

The present invention relates to improvements in corner-fastenings for bedsteads, and has for its main object to provide a simple, efficient and durable device of this type, the shell or housing of which is capable of being readily, economically and 15 conveniently struck up from sheet metal.

Another object of the invention is to produce a corner-fastening of the type mentioned, which permits of a convenient assembling of the bed and of a taking down of the 20 same without the employment of tools.

A further object of the invention is to provide a corner-fastening which effectively prevents, when once locked, longitudinal movement of the bed bottom supporting 25 iron rail in relation to the corner-fastening.

A still further object of the invention is to provide a corner-fastening of the character described that will permit of a reversal of the bed bottom supporting angle-iron 30 rail, that is to say with the horizontal flange of the latter either uppermost or lowermost.

With these and other objects in view, which will more fully appear as the nature of the invention is better understood, the 35 same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the 40 invention.

One of the many possible embodiments of the invention is illustrated in the accompanying drawings, in which:

Figure 1 is a side elevation of a portion of 50 a corner-post of a bedstead, with a corner-fastening, constructed in accordance with the present application for Letters Patent, in position thereon, the angle-bar being disposed with its horizontal flange uppermost; 55 Fig. 2 is a section taken on line 2—2 of Fig.

1; Fig. 3 is a section taken on line 3—3 of Fig. 2; Fig. 4 is a plan view of one of the ends of an angle-bar or rail to be supported by the corner-fastening; Fig. 5 is a side elevation of said bar; and Fig. 6 is a section 60 similar to the one illustrated in Fig. 2, the angle-bar being disposed with its horizontal flange lowermost.

In the drawings, the numeral 10 indicates a portion of a corner-post, to which the 65 corner-fastening is to be attached. The corner-fastening includes a bracket-like, hollow rectangular shell or housing 11, made, preferably, of one integral piece, for instance by stamping operations, and including a top 70 wall 12, an inner side wall 13, an outer side wall 14 and end members 15, one folded against the other. The outer end member abuts against the corner-post, the shell being attached to the latter, for instance, by 75 screws 16 passing through the said end members into the corner post. The shell is adapted to receive one end of the bed-bottom supporting side rail, in the form of an angle-bar 17, with its horizontal flange 18 either 80 uppermost or lowermost (Figs. 2 and 6). The vertical flange 19 of the angle-bar abuts in either case against the inner face of the outer side wall 14 of the shell. Adjacent its end, the flange 18 of the angle-bar is partly 85 cut off, as shown at 20, there being an oblong piece removed, the length of which is somewhat smaller than that of the top wall 12 of the shell, while its width is considerably less than the width of said top, for a purpose 90 hereinafter to be described. In the free edge 21 of the vertical flange 19 of the angle-bar is provided a notch 22, said notch being disposed within the shell 11 when the angle-bar is clamped to the latter, as clearly appears 95 from Figs. 1 and 3 of the drawings.

In the inner side wall 13 of the shell, immediately below the top wall 12, is provided a notch 23, into which the horizontal flange 18 of the angle-bar is adapted to be inserted 100 when uppermost (see Fig. 1). The purpose of this arrangement will appear hereinafter.

For the purpose of clamping the side rail to the shell of the corner-fastening, there is a bent lever 24 disposed within the shell, it being pivoted at 25 to ears 26, which are, preferably, made integral with the said shell, one of said ears extending in front and the other in rear of the bent lever, thereby securely holding the same against 110

movement in direction of the longitudinal axis of the shell. This bent lever is adapted to be extended into the notch 22 in the vertical flange of the angle-bar, when the horizontal flange 18 is positioned uppermost, it being provided with an upwardly extending arm 27, having a screw-threaded hole 28, the threads meshing with those of a screw bolt 29, for instance in the form of a thumb-screw, the bolt being adapted to be screwed against the inner face of the vertical flange 19 of the angle-bar. The head 30 of the thumb-screw is disposed outside of the shell 11, so that it may be easily manipulated. The thumb-screw extends through a hole 31 in the inner side wall 13 of the shell, the diameter of said hole being considerably larger than that of the screw bolt, in order to permit of proper movement of the latter in relation to the side rail of the bed bottom support. The end of the horizontal flange of the angle-bar is cut away at 20, so that it may clear the bent lever construction now described as the bar is being inserted into the shell.

The two shells on the corner-posts forming an end member of the bedstead may be connected in any suitable manner, for instance by an angle-bar 32, which is fastened in any suitable manner to the inner end walls 13 of the two shells.

The operation of the corner-fastening is as follows: When an angle-bar is to be inserted into the shell, the thumb-screw is first turned so that the free end of the clamping portion of the bent lever 24 drops below the upper edges of the ears 26, thereby permitting of convenient insertion of the angle-bar into the shell with the horizontal flange 18 in either position. When the angle-bar has been shifted into place with its horizontal flange uppermost (Fig. 1), the notch 22 in the vertical flange thereof is in alignment with the bent lever 24. When now the thumb-screw 30 is turned so that it moves toward the vertical flange of the said angle-bar, it causes the bent lever to turn on its pivot and to be seated in the notch 22. On further turning the thumb-screw in the same direction, the latter clamps the vertical flange of the angle-bar against the outer side wall 14 of the shell and the bent lever exerts pressure on the said vertical flange, clamping the horizontal flange of the

angle-bar against the top wall 12 of the shell.

Inasmuch as the bent lever is disposed within the notch 22, there is no likelihood of the angle-bar being accidentally disengaged from the shell. The end of the horizontal flange of the angle-bar being disposed within the notch 23, the weight of the bed bottom is carried mainly by the shell and not by the bent lever.

When the angle-bar is placed in position in the shell with the horizontal flange 18 lowermost, the bent lever exerts pressure on the said horizontal flange, clamping the vertical flange against the top wall of the shell. The portion 20 of the horizontal flange of the angle-bar is cut off in order to permit of the insertion of the angle-bar with its horizontal flange lowermost.

What I claim is:

1. A corner-fastening for bedsteads comprising a shell, an angle-bar of the bed bottom supporting frame extending into said shell, a bent lever pivotally carried by said shell for clamping said angle-bar against one of the walls of said shell, and means for operating said bent lever, said operating means clamping at the same time said angle-bar against another wall of said shell.

2. A corner-fastening for bedsteads comprising a shell for attachment to a corner-post, an angle-bar of the bed bottom supporting frame extending into said shell provided with a notch in the free edge of one of its flanges, a bent lever pivotally carried by said shell adapted to enter said notch, and means for operating said bent lever capable of exerting pressure upon the notched flange of said angle-bar.

3. A corner-fastening for bedsteads comprising a shell for attachment to a corner-post, an angle-bar of the bed bottom supporting frame extending into said shell provided with a notch in the free edge of one of its flanges, a bent lever pivotally carried by said shell adapted to enter said notch, and means for operating said bent lever capable of exerting pressure upon said angle-bar.

Signed at New York, in the county of New York, and State of New York, this 21st day of August, A. D. 1923.

DAVID WASSERMAN.
